UNITED STATES PATENT OFFICE.

ALEXANDER FORBES, OF GLASGOW, SCOTLAND.

PANTOGRAPH.

SPECIFICATION forming part of Letters Patent No. 743,980, dated November 10, 1903.

Application filed March 10, 1903. Serial No. 147,069. (No model.)

To all whom it may concern:

Be it known that I, ALEXANDER FORBES, of 118^a Renfield street, Glasgow, Scotland, have invented certain new and useful Improvements in Pantographs, of which the following is a specification.

This apparatus is constructed on the lines of an ordinary pantograph, but on a large scale. It is preferably made of wood, with the joints working on smooth metal surfaces, which method of joining has the effect of steadyng the apparatus to enable it to be used in an upright position, such as on a wall. A feature of the apparatus is the attachment to the enlarging end of a reservoir containing a supply of fluid pigment, such as ink, which percolates through a nozzle to a sponge, piece of felt, brush, or any similar porous substance.

Combined with apparatus as above described is a roll of wide paper, such as is used for printing newspapers, and the saturated sponge, &c., being dragged along the paper produces an enlargement with a thickness of line corresponding with the width of sponge, &c., used. A fresh surface of paper is rolled off for each enlargement.

The apparatus is intended for producing enlargements up to, say, twenty feet in diameter from small originals, which originals can be drawn on paper or preferably grooved out in wood. Provision is made for lifting the enlarging end of apparatus at detached parts of a design or between letters or words. This apparatus is specially suitable for doing what is known as "lightning cartoons" or for the instantaneous production of mammoth advertisements at public resorts. The operator would be concealed, and the only visible part of apparatus would be the enlarging end, which can be covered over to represent a human arm or hand. Another method is for the entire concealment of the operator and of the enlarging apparatus.

Figure 1 is a front elevation or front perspective view of a pantograph masked or concealed by the representation of a human arm and shown in the operation of producing an enlarged advertisement upon a sheet of paper which is carried upon rollers and mounted in a suitable box or framework. Fig. 2 is a similar but rear view with the pantograph

placed behind the sheet of paper which is to receive the advertisement when it is concealed, together with the operator manipulating it, who stands in the rear thereof. Fig. 3 is a section of the reservoir and inking device. Fig. 4 is a part side view of a spring arrangement for connecting the enlarging-arm to the pantograph and causing its outer end, with the inking device, to always press against the paper, all hereinafter more fully described.

The pantograph A is of the ordinary form, composed of four members a, b, c, and d, as illustrated in Figs. 1 and 2. A is pivotally connected to the wooden upright a², Fig. 2, by the pivot a³. To one end of the member b is mounted the tracing-point b', (shown in perspective in the drawings,) and the short member c, connecting the members a and b, is hinged at or near the midway of its connection, which enables the apparatus to be lifted off the paper when pulled by handles K. At the point where the member a is attached to the enlarging-arm d is introduced a bent spring e, which is illustrated in Fig. 4. The opposite end of the member a carries a weight or counterpoise a'. This spring tends constantly to keep the arm d pressed against the paper e'. The arm d at the outer end is mounted with an ink-reservoir f, which is illustrated in Fig. 3. This reservoir is intended to contain a supply of ink. The ink, which can be black or any color, is composed largely of some volatile liquid, such as methylated spirits, in order to cause it to penetrate clean through the paper and dry rapidly in the inking operation. The reservoir is filled through a nozzle g, and the outlet of this nozzle is plugged with a sponge or a ball of felt N, which is kept in position by a collar J. To give the sponge or ball of felt N the necessary resilience, a spring i is inserted within the nozzle and presses against the sponge.

The pantograph is operated by means of the handles K. The joints, respectively, of the pantograph work upon smooth metal disk surfaces.

In Fig. 1 the paper e' is unwound from the upper roller l and drawn down in front of a smooth surface m, and the ink representation is drawn on its exterior surface, as seen. The

slack paper is wound upon the lower roller $l'l'$, which, as shown in Fig. 1, is or may be provided with a crank-handle n for turning it. The exterior covering o , placed around 5 the enlarging end of the pantograph, represents a colossal arm, which in operation has a striking and animated appearance. The true operator is concealed below and in rear of the screen p .

- 10 In Fig. 2 the paper is unwound from upper roller behind a sheet of plate-glass, and the representation is drawn backward upon the back of the sheet of paper e' , which, being of such a nature, in conjunction with the special 15 ink, permits of the drawing penetrating clean through the paper and being fully seen to the front in the daylight, while at night the rays from a suitable artificial light are projected on its outer glass surface.
- 20 Fig. 5 shows the operator's box and the appearance to the spectators of the process described in Fig. 2, nothing being seen but the 25 design penetrating line by line through the paper from behind, and thus viewed in front through the sheet of plate-glass.

I claim—

1. In the production of animated posters or mammoth advertisements the combination of a pantograph having a printing-point and 30 a large arm constructed on an enlarged scale, a handle for operating and lifting printing-point at detached portions of design, a weight or counterpoise for balancing it, an inking-

reservoir mounted on the outer end of its enlarging-arm, a roll of paper suitably mounted 35 on horizontal rollers and so arranged to receive an ink drawing or representation on its front or rear surfaces, substantially as and for the purposes hereinbefore described and illustrated on the accompanying sheets of 40 drawings.

2. In the production of animated posters, or mammoth advertisements the combination of a pantograph formed with a spring and a hinged joint, a reservoir composed of a spherical chamber for holding or containing the ink, an inking-pad, a nozzle whereby the ink percolates to the inking-pad, a spring for giving the necessary resilience to the inking-pad and the means of retaining it in position, substantially as and for the purposes hereinbefore described and illustrated on the accompanying sheets of drawings.

3. A pantograph arranged in a vertical position and provided with a spring-pressed enlarging-arm, a yielding inking-pad, means for supplying ink to the pad, and means for balancing the pantograph.

In testimony whereof I have hereunto affixed my signature in presence of two witnesses.

ALEXANDER FORBES.
